SHELF

John G. L. Skar, Jamestown, N. Y., assignor to
Art Metal Construction Company, Jamestown,
N. Y.

Application May 18, 1932, Serial No. 612,032

7 Claims. (Cl. 211—135)

This invention relates to improvements in library book stacks, shelving or analogous structures of that sort in which the shelves are attached to the upright columns or parts of the supporting stack or structure by brackets or members connected to the shelves usually at their ends so as to serve also as end pieces or walls for confining the books or articles on the shelves. Such stacks or shelving structures are commonly 5 of knock down construction, or composed of parts which can be disconnected for storage and shipment and can be readily assembled at the place of installation and said brackets or members for attaching the shelves to their supports are separated from both the shelves and the supports and 10 adapted to be detachably connected thereto. An objection to this construction is that the supporting brackets, being relatively small separate parts, are apt to be misplaced or lost and cause 15 delay or inconvenience in erecting or installing the stacks or shelving.

One object of this invention is to provide a desirable but simple and economical construction in which the shelf supporting brackets or end pieces 25 for each shelf are attached to the shelf so that the brackets can be folded flat against the shelf to economize space in storing and shipping, and can be swung to their operative upright position ready for attachment to the supporting columns 30 or parts while, nevertheless, the brackets are connected to the shelf so that they can not become accidentally detached and lost or misplaced.

Other objects are to hinge the brackets to the shelf by interengaging integral parts of the shelf 35 and brackets and provide inexpensive means which prevent disengagement of the hinge connections and also operate to releasably retain the brackets in their upright, operative position to facilitate the attachment of the shelves to their supports; and also to improve library stacks or 40 shelving structures in the other respects herein-after described and set forth in the claims.

In the accompanying drawing:

Fig. 1 is a fragmentary, front elevation on a 45 reduced scale of a library stack or shelving structure embodying the invention.

Fig. 2 is a plan view of one end of a shelf with the supporting bracket in operative position 50 thereon.

Fig. 3 is an elevation thereof showing by full and broken lines respectively the folded and upright positions of the bracket.

Fig. 4 is a transverse section on line 4—4, Fig. 2. 55 Fig. 5 is a detail section on an enlarged scale

showing one of the hinge connections between the shelf and the bracket.

Fig. 6 is a similar detail view showing the folded position of the bracket.

10 represents the shelves, and 11 the columns 5 or upright supports of a library stack or shelf structure, and 12 represents brackets at the opposite ends of each shelf and attached to the shelf and to the columns 11 so as to support the shelves from the columns. The shelves may 10 be of any usual or suitable construction and, as shown, each shelf is made from sheet metal and provided along its front and rear edges with depending stiffening flanges 13 having inturned, doubled bottom edges. The shelf shown is also 15 provided with downturned, vertical flanges 14 at its ends.

Each bracket is preferably formed from a single sheet metal blank provided with outturned front and top edges which stiffen the 20 bracket and provide a smooth finish for these edges. Preferably, the brackets are located at opposite ends of each shelf, and each bracket is hinged at its lower edge to the shelf by integral hinge lugs 15 which are bent to project inwardly 25 at right angles from the lower edge of the bracket and extend through narrow slots 16 in the horizontal plate of the shelf parallel with and spaced inwardly from one end of the shelf. The lugs 15 are offset downwardly below the bottom edge 30 of the bracket a distance about equal to the thickness of the shelf plate and are adapted to turn in the slots 16 to permit the bracket to be swung from its upright position to a position in which it lies flat upon the shelf. When the bracket is 35 in its upright position, the lugs will bear against the underside of the shelf plate and prevent the bracket from swinging outwardly beyond the intended upright position. The lugs 15 are of a length adapting them to be inserted through the 40 slots 16 and the two lugs 15 of the bracket are notched at their corresponding ends, as indicated at 17, Figs. 5 and 6, so that after the lugs 45 have been inserted through the slots 16, the bracket can be shifted transversely of the shelf to cause the notched ends of the lugs to underlie or engage the shelf plate at the adjacent ends of the slots 16 and thus prevent the removal of the lugs from the slots except by first shifting the bracket until the notched ends of the lugs 50 clear the ends of the slots 16.

Such shifting of the bracket to releasing position may be prevented by suitable retaining means on the shelf arranged to engage one or both of the hinge lugs 15 so as to prevent the 55

bracket from being shifted to the position necessary to allow the lugs to pass through the slots 16 in the shelf. These retaining means may consist of one or more metal pieces 18 riveted or otherwise secured to the adjacent end flange 14 of the shelf and having legs 19 projecting inwardly so as to engage the inner ends of the hinge lugs. Preferably, each inwardly projecting leg 19 extends at an angle to the plane of movement of the adjacent end of the hinge lug during the swinging movement of the bracket so that when the bracket is swung upwardly, the ends of the lugs will spring the legs 19 and place them under tension, thereby causing the legs 19 to bear forcibly against the ends of the hinge lugs and resist the swinging of the bracket. Preferably, also the upper edges of the legs 19 are bevelled, as indicated at 20, Figs. 5 and 6, whereby, when the bracket is in its upright position, these bevelled edges will be pressed against the ends of the hinge lugs, which then extend horizontally parallel with the bevelled edges, the engagement of the bevelled edges with the lugs serving to effectually hold the bracket in the upright position but nevertheless permitting the bracket to be swung down simply by the application of sufficient force to spring the hinge lugs out of engagement with the bevelled edges.

The retaining means thus perform two functions. First, they prevent the supporting bracket from being shifted transversely of the shelf to a position to allow the lugs to be withdrawn from the slots 16, and therefore prevent the disengagement of the bracket from the shelf. Second, the retaining means by their frictional and snap engagement with the hinge lugs, as explained, releasably retain the bracket in its upright operative position on the shelf. The retaining means can be attached to the shelf after the hinge lugs of the bracket have been inserted into the slots 16 and shifted to their operative positions in the slots with the notched ends of the lugs underlying the adjacent ends of the slots, or the retaining means could be attached to the shelf with the legs 19 thereof extending in a position to permit the insertion of the hinge lugs into the shelf slots 16, after which the legs 19 can be bent to their final position in the described cooperative relation with the ends of the hinge lugs.

The brackets 12 are adapted to be connected with the supports or columns 11 of the stack or shelving structure in any suitable manner. For instance, the brackets may be formed for this purpose, as disclosed in Letters Patent, Number 1,195,295, issued August 22, 1916, to P. G. Turner, assignor to Art Metal Construction Co., according to which each bracket is provided at the lower portion of its rear edge with a rearwardly projecting lug 21 adapted to enter one of a series of slots 22 in one of the supports 11 and the bracket is provided at the upper portion of its rear edge with rearwardly projecting hooks 23 adapted to hook into other slots in the support 11. By the construction described, the shelves can be installed in position on the columns or supports simply by swinging the brackets to their upright positions and inserting the lug and hooks of each bracket in the appropriate slots in one of the columns or supports and the shelves can be readily disconnected from the columns. When the shelves are disconnected from the columns, the brackets can be folded down flat against the shelves to facilitate storing and shipping of the shelves.

I claim as my invention:

1. The combination of a shelf, a supporting bracket therefor having an integral hinge lug entering and shaped to turn in a slot in the shelf to permit the bracket to swing from a position substantially parallel with the shelf to a position substantially perpendicular to the shelf, said hinge lug being adapted to pass through said slot and having a notched end adapted by shifting the bracket relatively to the shelf to engage the adjacent edge of the slot to prevent withdrawal of the lug from the slot, and a retaining member on the structure arranged to prevent the bracket from being shifted to a position to disengage the notched end of said lug from the end of the slot.

2. The combination of a shelf, a supporting bracket therefor provided with an integral hinge lug entering and shaped to turn in a slot in said shelf whereby the bracket is hinged to the shelf to swing relatively to the shelf from a position substantially parallel with the shelf to a supporting position at an angle to the shelf, and a retaining member which is fixed on the structure and automatically coacts with said hinge lug to releasably hold the bracket in one of its positions on the shelf.

3. The combination of a shelf and a bracket, one of said parts having a hinge lug entering and shaped to turn in a slot in the other part whereby said parts are hinged together to swing to and from positions substantially perpendicular to each other, and a retaining member on the part having the slot and arranged to yieldingly engage said hinge lug for releasably retaining said bracket in one of its positions.

4. The combination of a shelf and a bracket, one of said parts having a hinge lug entering and shaped to turn in a slot in the other part whereby said bracket is adapted to swing from a position substantially parallel with the shelf to a position substantially perpendicular to the shelf, and a yieldable retaining member on the part having the slot and arranged to bear yieldingly against said hinge lug for releasably retaining said bracket in its perpendicular position, the engagement of the retaining member with the hinge lug also preventing withdrawal of said hinge lug from said slot.

5. The combination of a shelf and a bracket, one of said parts having a hinge lug entering and shaped to turn in a slot in the other part to permit the bracket to swing from a position substantially parallel with the shelf to a position substantially perpendicular to the shelf, said lug having a notch in one end arranged to straddle one edge of the slot, and a retaining member on the structure arranged to prevent disengagement of the edge of said slot from said notch in the lug.

6. The combination of a shelf and a bracket, one of said parts having a hinge lug entering and shaped to turn in a slot in the other part to permit the bracket to swing from a position substantially parallel with the shelf to a position substantially perpendicular to the shelf, said lug having a notch in one end arranged to straddle one edge of the slot, a retaining member on the structure arranged to prevent disengagement of the edge of said slot from said notch in the lug, and said retaining member adapted to bear yieldingly against said lug to releasably hold said bracket in its perpendicular position.

7. The combination of a shelf and a bracket, one of said parts having a hinge lug entering

and shaped to turn in a slot in the other part to permit the bracket to swing from a position substantially parallel with the shelf to a position substantially perpendicular to the shelf, said bracket and shelf having integral portions which are interengaged by shifting the bracket relatively to the shelf in a direction transverse to

its direction of swinging movement and which when engaged prevent withdrawal of said hinge lug from said slot, and a retaining member on the structure arranged to prevent disengagement of said interengaging portions and the withdrawal of said hinge lug from said slot.

JOHN G. L. SKAR.
